SKEIN WINDING REEL

Montgomery B. Penman, Bloomsburg, Pa., assignor to The Magee Carpet Company, Bloomsburg, Pa., a corporation of Pennsylvania

Application July 21, 1953, Serial No. 369,444

14 Claims. (Cl. 242—53)

This invention relates to improvements in skein winding reels and more particularly to a winding reel having expandible and contractable paddles to facilitate the removal of the skeins from the reel.

It is an object of the invention to provide a winding reel for skeins of yarn having expandible and contractable paddles with mechanism for expanding and contracting the paddles and a movable bearing post supporting one end of the reel shaft having means to swing the post outwardly from the end of the shaft to permit easy removal of the skeins from the reel when the paddles are contracted.

A further object of the invention resides in providing a winding reel having a fixed bearing for supporting one end of the reel shaft and a movable bearing for supporting the other end of the shaft with means for adjusting the shaft to insure alinement with the movable bearing.

A still further object of the invention resides in providing means for automatically locking the yarn spools on their spindles during the winding of the yarns on the reel to prevent accidental dislodgment of the spools from the spindles.

Another object of the invention resides in providing a winding reel having mechanism for expanding and contracting the paddles which is simple and durable in construction, reliable and efficient in operation and requires a minimum amount of labor.

Other objects and advantages of the invention will be apparent during the course of the following specification.

In the accompanying drawings forming a part of this specification and in which like numerals are employed to designate like parts throughout the same,

Figs. 1 and 1A taken together are a front elevational view of the winding reel,

Fig. 2 is an end view of the same,

Fig. 3 is a section taken on line 3—3 of Fig. 1A,

Fig. 4 is a sectional view of the spool locking mechanism,

Fig. 5 is a fragmentary front view of the spool locking mechanism,

Fig. 6 is a plan view of one of the reel disks,

Fig. 7 is a plan view of the other side of the reel disk shown in Fig. 6,

Fig. 8 is an enlarged longitudinal sectional view of one of the reel disks showing the different positions of the expanding mechanism,

Fig. 9 is a sectional view of the gear housing and gear mechanism,

Fig. 10 is an end view of the gear mechanism, and,

Fig. 11 is a section taken on line 11—11 of Fig. 10.

Referring to the drawings wherein for the purpose of illustration a preferred embodiment of the invention is shown the numeral 5 denotes the shaft of the winding reel, one end of which is supported by a fixed bearing 6 in the front wall 7 of gear housing 8 and a bearing 9, Fig. 11, mounted on adjustable cross bars 9'. The cross bars are attached to side walls 10 of the housing by bolts 11 for vertical adjustment and studs 12 mounted in lugs

2

13 attached to the side walls have bearing engagement with the upper edge of the cross bars for adjusting the cross bars downwardly and upwardly when the bolts 11 are loosened. The opposite end of shaft 5 is supported in a conical bearing 14 mounted on the upper end of post 15. Post 15 is pivotally mounted at 16 on the base frame 17 to swing outwardly from the end of shaft 5. The post is actuated by a pneumatic cylinder 18 pivotally attached at 19 to the base 17 and the piston of the cylinder is attached at 20 to the post. The cylinder is connected to a source of compressed air, not shown, for moving the piston in opposite directions to swing the post and bearing 14 into and out-of supporting position. An angularly disposed U-shaped frame 21 attached to the end of base 17 limits the outward movement of post 15 and a bumper block 22 attached to the base retards the outward movement of the post and absorbs the shocks.

A series of disks 23 are mounted on shaft 5 in spaced apart relation and each disk has one face provided with a series of radial grooves 24, more clearly shown in Fig. 6, in which are slidably mounted extensible arms 25 having bifurcated ends 26 for attaching paddles 27 to the arms. The arms 25 are retained in the grooves by cover plates 28 attached to the disks by studs 29 and formed integral with the inner ends of the cover plates are laterally projecting lugs 30. Toggle joints composed of links 31 and 32 having one end pivotally connected to lugs 30 and their opposite ends pivotally connected to lugs 33 formed integral with arms 25 move the arms to an extended or contracted position. The toggle joints of each disk are connected with the corresponding toggle joints of the other disks by connecting bars 34 which are connected to the pivot bolts 35 of the toggle joints and extend through slots 36 and 37 in the arms 25 and disks 23. When the toggle joints are moved in one direction the arms 25 are extended beyond the edge of the disks thus moving the paddles 27 to an expanded position and when moved in the opposite direction the arms 25 are retracted thus moving the paddles to a contracted position.

A collar 38 is slidably mounted on shaft 5 adjacent the disk 23 confronting the end wall 7 of gear housing 8. A series of lugs 39 project radially from the collar and are connected by links 40 with the pivot bolts 35 of the toggle joints of the end disk adjacent the collar. The collar 38 is reciprocated on the shaft 5 to actuate the toggle joints by a yoke 41 which straddles the collar. A split ring 42 is mounted on the collar and has projecting pins 43 which engage in slots 44 formed in the arms of the yoke to establish connection between the yoke and collar. The yoke is affixed to the upper end of a lever 45 pivotally mounted as at 46, to a bracket 47 attached to the wall 7 of the gear housing. The lower end of lever 45 is pivotally connected to piston rod 48 of pneumatic cylinder 49 pivotally attached to the base frame 17. The cylinder is connected to a source of compressed air to move the piston rod in both directions so as to move the lever 45 and operate the yoke to slide the collar 38 back and forth.

60 A spindle frame or rack 50 is attached to the rear of the base frame 17 consisting of an upright 51 supporting one end of a cross bar 52 having its opposite end attached to the top of gear housing 8. The cross bar 52 is inclined in a forward direction and attached to the top thereof is an angle bar 53 on which are mounted a series of spindles 54, in spaced apart relation, for receiving the yarn packages or spools 55, shown in Fig. 4, the spools having the usual flanges 55'. A horizontal bar 56 is supported above the cross bar 52 by end members 57 attached to the ends of the cross bar and attached to the bar 56, at spaced apart intervals, are depending dividing plates 58 and between the plates in vertical alinement with the spindles

54 are depending hooks 59 for guiding the yarn as it is unwound from the spools. Attached to and extending from the forward edge of cross bar 52 are a series of brackets 60 having spaced guide rollers 61 for supporting the reciprocating guide rod 62 from which extend a series of guide arms 63 having eyes 64 at their outer ends through which the yarns are threaded.

As shown in Figs. 9, 10 and 11 the gearing for operating the winding reel is contained within the gear housing 8. Mounted on the shaft 5 of the reel is a double groove pulley 65 which is driven by a belt 66 connected to a double groove pulley 67 mounted on idler shaft 68. A pair of change speed pulleys 69 and 70 are mounted on the idler shaft and are driven by a belt 71 connected with the change speed pulleys 72 and 73 mounted on shaft 74 of a motor 75. One end of reciprocating guide rod 62 extends through an opening 76 in the front wall 7 of the gear housing being pivotally connected at 77 to eccentric 78 mounted on the upper end of shaft 79 journaled in brackets 80 and 81. A bevel gear 82 fixed on shaft 79 below bracket 80 is in mesh with bevel gear 83 mounted on shaft 84 journaled in bearings 85 and 86. A sprocket wheel 87 mounted on shaft 84 is driven by sprocket chain 88 connected to a drive sprocket 89 mounted on the reel shaft 5. An idler sprocket 90 engaged with the sprocket chain is provided to take up the slack in the chain.

A locking mechanism for retaining the yarn packages or spools on their spindles is shown in Figs. 4 and 5. A lock bar 91 extends longitudinally of the spindle frame above the cross bar 52 and to the rear of the spindles 54 that support the yarn spools 55. The bar is provided at its ends with pivot pins 92 journaled in brackets 93 attached to the end members 57. An arm 94 attached to and depending from the ends of pivot pins 92 connects with one end of a coil spring 95 having its opposite end attached to a bracket 96 secured to cross bar 52. The tension of coil springs 95 normally swing the lock bar 91 so its lower edge is disposed over the flange of the yarn spool 55, thus retaining the yarn spools on their spindles and preventing accidental removal of the spools from the spindles due to the pull of the yarn on the spool during the winding operation. A dog 97 affixed to one of the pivot pins 92 and depending therefrom is adapted to be engaged by one end of a latch lever 98 when the lock bar 91 is swung rearwardly and the latch lever is in a horizontal position thereby holding the lock bar free of the spool flange so the spools may be removed from the spindles. The latch lever 98 is pivotally suspended from bracket 93 by arm 99 attached to the lever intermediate its ends and is normally disposed in a horizontal position. A latch release lever 100 having its upper end disposed beneath the outer end of the latch lever is pivotally mounted in a bracket 101 attached to the top of gear housing 8. A yoke 102 extending laterally from the lower end of lever 100 engages with an arm 103 attached to yoke 41, so that when yoke 41 is moved to expand the paddles of the reel the latch release lever is moved to release the latch dog 97 to permit the lock bar 91 to assume a locking position under the action of springs 95. The actuation of the latch lever to release the latch dog is performed by plate 104 attached to the upper end of release lever 100 which has a beveled edge 105 in engagement with the lower edge of the latch lever 98 so that when release lever 100 is moved the latch lever is raised by the beveled edge of plate 104. A shoulder 106 at the upper end of the beveled edge limits the movement of the release lever in one direction and a coil spring 107 having one end attached to plate 104 and its opposite end to cross bar 52 swings the release lever in the opposite direction when yoke 41 is moved to contract the paddles of the reel.

The pneumatically operated cylinders 18 and 48 are controlled by conventional foot operated valve mechanisms for admitting compressed air to either end of the cylinders.

In operation, the packages or spools of yarn are

mounted on the spindles 54 and the strands of yarn drawn from the spools over hooks 59 disposed above the spools and then threaded through the eyes 64 of guide arms 63 before being attached to one of the paddles 27 of the reel. The reel is rotated by starting the motor 75 which drives the reel shaft 5. During the reeling operation the rod 62 is reciprocated so that the guide arms 63 move the strands of yarn back and forth to perform the skein formation in the usual manner. When all of the 10 yarn from the spools has been wound on the reel cylinder 49 is actuated to move the collar 38 to the right which through operation of the links 40 and connecting bars 34 operates the toggle links 31, 32 to simultaneously retract the arms 25 of disks 23 to contract the paddles 27 so the skeins of yarn may be easily removed from the reel. To permit the skeins to be removed from the end of the reel, cylinder 18 is operated to swing post 15 to the left or away from the end of the reel thus removing the bearing 14 from engagement with the end of shaft 5. After 15 removal of the skeins of yarn the cylinder 18 is operated to move post 15 to the right and bring the bearing 14 into engagement with the end of shaft 5 and then collar 38 through operation of cylinder 49 is moved to the left to move the paddles 27 to expanded position. When the 20 paddles 27 of the reel are expanded by movement of collar 38, release lever 100 for the latch lever 98 is moved by arm 103 attached to yoke 41 to release the latch lever from engagement with dog 97 thus allowing spring 95 to swing the lock bar 91 so its lower edge engages over the 25 flanges of the spools 55 to retain the spools on their spindles until the winding operation is completed. When the paddles of the reel are contracted, release lever 100 is moved by spring 107 to allow latch lever 98 to swing into engaging position with dog 97, as the lock bar 91 is 30 manually swung outwardly to a non-locking position. Thus, it is seen the latch lever holds the lock bar in a non-locking position while the empty spools are removed from the spindles and replaced with full spools of yarn.

Having thus described my invention, I claim:

40 1. A skein winding reel comprising a rotatable shaft, a series of fixed disks mounted on said shaft, a series of radially slideable arms mounted in each disk for movement beyond the periphery of the disk, paddles attached to the outer ends of the corresponding arms of said disks, 45 toggle joints connected to said arms and said disks for extending and retracting said arms in a perpendicular plane, reciprocating bars connecting the corresponding toggle joints of each disk for simultaneous movement, a movable collar on said shaft adjacent one of the end disks, and means connecting said collar with said toggle joints of said end disk for actuating the toggle joints upon movement of said collar.

45 2. A skein winding reel of the character described in claim 1 including a pivoted lever having a yoke connected with said collar, and means for moving said lever to move said collar.

50 3. A skein winding reel of the character described in claim 1 including a pivoted lever having a yoke connected with said collar, and pneumatic operating means connected with said lever for actuating said lever to move said collar.

55 4. A skein winding reel comprising a rotatable shaft, expansive and contractable paddles mounted on said shaft, a spindle rack having a series of spindles mounted above said paddles, yarn spools mounted on said spindles having their yarns connected to one of said paddles, a lock bar extending longitudinally of said spindle rack and pivotally mounted thereon, means normally holding said lock bar in locking engagement with the flanges of said yarn spools, a latch lever for holding said lock bar in non-locking position, and means for simultaneously expanding said paddles and releasing said latch lever.

60 5. A skein winding reel comprising a rotatable shaft, expansive and contractable paddles mounted on said shaft, a spindle rack having a series of spindles mounted

above said paddles, yarn spools mounted on said spindles having their yarns connected to one of said paddles, a lock bar extending longitudinally of said spindle rack and pivotally mounted thereon, means normally holding said lock bar in locking engagement with the flanges of said spools, a latch lever for holding said lock bar in non-locking position, a release lever for actuating said latch lever to release said lock bar, means for expanding and contracting said paddles, and a movable collar on said shaft for simultaneously operating said expanding means and said release lever.

6. A skein winding reel comprising a rotatable shaft, a series of disks mounted on said shaft, a series of radially slidable arms mounted in each disk for movement beyond the periphery of the disk, paddles attached to the outer ends of the corresponding arms of said disks, toggle joints connected to said arms and said disks for extending and retracting said arms in a perpendicular plane, reciprocating bars connecting the corresponding toggle joints of each disk for simultaneous movement, a collar movably mounted on said shaft adjacent one of the end disks, links connecting said collar with the toggle joints of the end disk, a pivoted lever having a yoke connected with said collar, and pneumatic means for operating said lever to reciprocate said collar.

7. A skein winding reel comprising a rotatable shaft, fixed bearings supporting one end of said shaft, a bearing movable into and out of supporting engagement with the other end of said shaft, means for moving said movable bearing into and out-of engagement with the end of said shaft, a series of disks mounted on said shaft, a series of radially slidable arms mounted in each disk, paddles attached to the outer ends of the corresponding arms of said disks, toggle joints connected to said arms and said disks for extending and retracting the arms in a perpendicular plane, reciprocating bars connecting the corresponding toggle joints of each disk for simultaneous movement, a collar movably mounted on said shaft, links connecting said collar with said toggle joints, and means for moving said collar to expand and contract said toggle joints.

8. A skein winding reel comprising a rotatable shaft, a pair of bearings supporting one end of said shaft, a movable bearing supporting the other end of said shaft, means for moving said bearing into and out-of engagement with the end of said shaft, a series of disks mounted on said shaft, a series of radially movable arms mounted in each disk, paddles attached to the outer ends of the corresponding arms of said disks, toggle joints connected to said arms and said disks, connecting rods between the corresponding toggle joints of said disks, a collar slidably mounted on said shaft adjacent one of the end disks, means connecting said collar with said toggle joints for actuating the same, a spindle rack having a series of spindles mounted above said paddles, yarn spools mounted on said spindles having their yarns connected to one of said paddles, a hingedly mounted lock bar extending longitudinally of said spindle rack, means normally holding said lock bar in locking engagement with the flanges of said yarn spools, a latch lever for holding said lock bar in non-locking position, and a release lever for said latch lever operated by said collar.

9. A skein winding reel comprising a rotatable shaft, a series of paddles extending longitudinally of said shaft in parallel spaced relation thereto, a plurality of toggle joints at spaced apart intervals connecting said paddles to said shaft, reciprocating means connecting said joints for simultaneous movement, means for actuating said toggle joints to radially move said paddles towards and from said shaft in parallel relation thereto, and means for guiding the movement of said paddles in a straight radial plane at right angles to the plane of said shaft.

10. A skein winding reel comprising a rotatable shaft, expandable and contractible paddles mounted on said shaft, a spindle rack having a series of spindles mounted above said paddles, yarn spools mounted on said spindles having yarns connected to one of said paddles, a movable lock bar mounted above said spindle rack, means normally holding said lock bar in locking engagement with the flanges of said yarn spools, means for holding said lock bar in non-locking position, and means for simultaneously expanding said paddles and releasing said last mentioned means.

11. A skein winding reel comprising a rotatable shaft, expandable and contractable paddles mounted on said shaft, a spindle rack having a series of spindles mounted above said paddles, yarn spools mounted on said spindles having yarns connected to one of said paddles, a movable lock bar mounted above said spindle rack for movement into and out-of locking engagement with the flanges of said yarn spools, and releasable means for holding said lock bar in non-locking position.

12. A skein winding reel comprising a shaft rotatably mounted at one end, a series of paddles parallel to the axis of said shaft, expanding and contracting means connecting said paddles to said shaft, means for operating said expanding and contracting means, a post pivotally mounted for swinging movement towards and from the free end of said shaft, a conical bearing carried by said post for revolutely supporting the free end of said shaft, and means for swinging said post to engage and disengage 40 said conical bearing with the free end of the shaft.

13. A skein winding reel of the character described in claim 12 including pneumatic means for swinging said post.

14. A skein winding reel of the character described in claim 12 including an adjustable bearing rotatably supporting said shaft that is adjustable to aline the free end of said shaft to engage the conical bearing carried by said post.
